UNITED STATES PATENT OFFICE.

HENRY J. PALMER, OF NEW YORK, N. Y., ASSIGNOR OF ONE-HALF TO
CHESTER ROBINSON, OF NEW YORK, N. Y.

ARC-LIGHT DISTRIBUTER.

SPECIFICATION forming part of Letters Patent No. 772,745, dated October 18, 1904.

Application filed February 15, 1904. Serial No. 193,568. (No model.)

To all whom it may concern:

Be it known that I, HENRY J. PALMER, a citizen of the United States, and a resident of the city of New York, borough of Manhattan, in 5 the county and State of New York, have invented a new and Improved Arc-Light Distributer, of which the following is a full, clear, and exact description.

My invention relates to means for distributing light and admits of general use, but is 10 peculiarly applicable in the case of arc-lights, for the reason that in such lights the illuminating-surface due to the use of carbon is comparatively small.

15 Reference is to be had to the accompanying drawings, forming a part of this specification, in which similar characters of reference indicate corresponding parts in all the figures.

Figure 1 is a vertical central section upon 20 the line 1 1 of Fig. 2 looking in the direction of the arrow and showing one of my distributers in use. Fig. 2 is a horizontal section upon the line 2 2 of Fig. 1 looking in the direction of the arrow, and Fig. 3 is a horizontal 25 section upon the line 3 3 of Fig. 1 looking in the direction of the arrow.

The annular top portion 4 is provided with an annular flange 5, provided with apertures 6, and said top portion is provided with eyes 30 7, connected with chains 8, whereby the entire device is suspended or otherwise mounted. A plurality of prismoids 9, each provided with flat faces or facets 10, are disposed equidistant from the carbons 11, used for 35 supplying the light. The faces 10 of each prismoid are inclined relatively to each other by an angle, preferably obtuse. I find that good results ensue when these faces are inclined about one hundred and twenty degrees 40 relatively to each other, as indicated. I do not limit myself, however, to any particular angle. The spaces between the prismoids 9 are closed by means of glass plates 12. A rotund cap 13, provided with glow-holes 14, is 45 mounted upon the bottom of the device. The metallic members 15 serve to hold the several parts in position. The top and bottom portions of each prismoid 9 are provided with facets 9^a 9^b, which are inclined relatively to

a horizontal plane for the purpose of still 50 further diffusing the light.

The light-distributer may, if desired, be placed at street intersections, the glass plates 12 being disposed in the general directions of the streets. It is especially designed for 55 street intersections and other points where lamps are spaced far apart. The carbons 11 being energized in the usual manner, the light radiates from them and strikes the faces 10. The faces 10 are white. This glow may be 60 given them in any desired manner—for instance, by painting them or giving them a surface of white enameline or even by making the prismoids 9 of a material white in color. The light radiating in all directions 65 and striking the several faces or facets 10 is caused to be diffused and in a sense concentrated in the directions of the several streets—that is to say, all of the light-rays which go from the carbon directly outward through 70 the glass plates 12 will be unobstructed, whereas a considerable proportion of the rays which strike the faces 10 of the prismoids is likewise caused to pass outward through the glass plates 12, being thus superadded to the 75 light passing directly from the carbons. The fact is that the light is so distributed as to cause a bright illumination in certain definite directions, and yet the light passing in those directions is so diffused as to be comparatively 80 easy upon the eyes.

The annular member 4 is concave, as shown, its under surface being light in color, preferably white, and adapted to reflect the light downward. The facets 9^a 9^b, disposed, respectively, at the top and bottom of each prismoid, serve still further to break up and diffuse the light. The upper concave surface of the metallic member acts likewise, the result being that the light is still further broken 90 up and diffused. The light which passes downward through the glow-holes 14 instead of producing a circle of illuminating spots upon the pavement causes the space below the distributer to be lighted up with a general glow.

It will be understood, of course, that in practically all arc-lights, whether operated

by direct or alternating currents and whether inclosed or open, a large proportion of the light is projected upward and the rest concentrated downward within a radius of a few 5 feet. This is remedied by my device in the manner above described upon the principle that the light is broken up and diffused and yet to some extent concentrated in definite directions.

10 My device further acts as a globe, forming practically the same function as a glass globe in addition to those above described.

While I show the device as applied to arc-lights, it may of course be used in connection 15 with lights of other kinds, and I do not limit myself in the character of other lights employed.

Having thus described my invention, I claim as new and desire to secure by Letters Patent—

20 1. In a light-distributer, the combination of a source of light, a cap disposed below the same and provided with a reflecting-surface facing said light and also provided with glow-holes for throwing the light downward, and 25 mechanism provided with reflecting-surfaces disposed adjacent to said cap for the purpose of diffusing the light reflected therefrom, thereby causing said light to pass downwardly through said glow-holes.

30 2. In a light-distributer, the combination of a source of light, a plurality of prismoidal members disposed adjacent to said source of light and provided with white surfaces disposed at obtuse angles relatively to each 35 other for the purpose of diffusing light, said prismoidal members being vertical and provided at their respective tops and bottoms

with facets inclined relatively to said source of light, reflecting mechanism disposed above and below said prismoidal members, and glass 40 plates connecting said prismoidal members together.

3. In a light-distributer, the combination of a source of light, a plurality of solid prismoids disposed adjacent thereto and provided 45 with reflecting-surfaces inclined relatively to each other and provided with facets for the purpose of concentrating a diffused light in definite predetermined directions, said prismoids being also provided with rotund surfaces, and plates of glass of rotund conformity disposed adjacent to said facets and connecting said prismoids together so that the entire structure presents a substantially cylindrical form. 55

4. In a light-distributer, the combination of a plurality of solid prismoidal members each having two surfaces inclined relatively to each other at an obtuse angle and painted white, and being of longitudinal form, each 60 of said members being further provided at its ends with facets capable of reflecting light, a source of light disposed adjacent to said members, and reflecting mechanism disposed adjacent to said facets for the purpose of diffusing light reflected therefrom. 65

In testimony whereof I have signed my name to this specification in the presence of two subscribing witnesses.

HENRY J. PALMER.
